CLARIFICATION AND DEMINERALIZATION PROCESS FOR B-MOLASSES AND SIMILAR MATERIALS CONTAINING CONCENTRATED IMPURITIES

Ernst W. Kopke, New York, N. Y., assignor to Ultra-Sucro Company, New York, N. Y., a partnership

Application July 30, 1956, Serial No. 600,778

11 Claims. (Cl. 127—46)

This invention relates to processes of manufacturing sugar and more especially to the clarification and demineralization of sugar solutions so as to overcome restrictions existing in sugar factories, especially but not exclusively in raw sugar factories. They also exist in beet sugar manufacture to extents and degrees which differ due to the difference in the amounts and kinds of impurities in beets as compared with cane.

The restrictions lower considerably the yield of sugar from the raw material.

Also, these restrictions have resulted in molasses which contain bacterial and other impurities that restrict the use of molasses.

Moreover, the impurities themselves while undesirable in the sugar and molasses have long been known to be useful; but their usefulness has been limited because of the inability to effectively separate them from the molasses.

Reverting to the matter of increasing sugar yields, various mineral salts which are present always in considerable amounts in sugar liquors (generally referred to as ash forming material) exert a restrictive effect on final-stage crystallization of sugar from the solution.

That gains in sugar yields are attainable through the removal of mineral salts has been abundantly proved in operations of various sorts in both beet and cane sugar production. However, demineralization, as usually practiced, has been costly, chiefly because of the need for regenerants such as caustic soda and acid when the removal of mineral salts is accomplished by means of ion exchange. Therefore, commercial adaptations have not proceeded as rapidly as the attainable, and proved, gains in sugar yield would appear to warrant. The mode of incorporating demineralization according to my present process involves distinct economies as well as functional advantages, particularly in the final stages of crystallization, and results in substantial economic benefits.

One objective of my process is to provide for clarification and demineralization of sugar bearing solutions at a processing stage where the maximum gain in increased yield of sugar, pure molasses and separation of the impurities from the molasses is accomplished at minimum cost in equipment and in operation.

Another objective is to incorporate a clarification and demineralization process in raw cane sugar factories in such manner as to maintain the present standard of the product and the present commercial position of the producer and refiner.

Another objective is to provide the clarification and demineralization process to existing factories so that the present equipment and methods remain undisturbed while the over-all results in process functions, as applying especially to the latter stages of crystallization and curing, are improved, whereby the yield of sugar is increased, purer molasses is obtained and more complete separation of impurities made possible.

Other objects include improving the quality of the final sugars and final molasses; separation of impurities from

2

the molasses and sugar with separate collection thereof, and increasing the capacity of existing final stage equipment such as vacuum pans, crystallizers and centrifugals.

Other objects and advantages will become apparent as the invention is described in connection with the drawings.

5 In the drawings:

Fig. 1 is a flow diagram of a raw cane sugar manufacturing process in which is incorporated a clarification and a demineralization stage according to the present process.

10 Fig. 2 is a detailed flow diagram of the clarification stage.

Fig. 3 is a fragmentary sectional view of a centrifugal separator bowl.

15 Fig. 4 is a detailed flow diagram of the demineralization stage.

Accomplishment of the above-mentioned objectives by my invention involves, primarily:

(1) Clarification and demineralization of "B" molasses or any other molasses or syrup just before it is to be subjected to final vacuum pan boiling and crystallization.

20 (2) Employment of an ion exclusion facility which utilizes a single resin bed to remove mineral salts and other non-sugars while retaining within the resin bed, the sucrose solute which is then removed by water rinse, avoiding thereby the use of costly regenerants.

(3) Employment of a step or series of steps which insures and safeguards the production of raw sugar from cane in areas where adherence to the raw sugar standard of production is commercially desirable.

Thousands of cycles of successful and economical demineralization of clarified molasses in accordance with my invention have proved the dependability, high efficiency and economy of the principle of removing the mineral salts by ion exclusion. Major economies in equipment and operation, which are unattainable when using ion exchange, are provided; and purer molasses and sugar, as well as a separation of the impurities as a separate by-product are attained, by use of a special resin which retains by adsorption within the resin the low ion sucrose solute while the highly ionized solutes of the mineral salts and other non-sugars are excluded.

45 A typical cycle of my ion exclusion stage embodies:

(i) The passing of a batch of molasses through an ion-exclusion resin bed which is adsorbent of the sucrose solute so as to retain within the special porous resin structure of the bed, the sucrose solute while the high ion salts in solution, and other non-sugar materials, pass through;

50 (ii) Upon and following the molasses, introducing water which removes the sucrose solute from the adsorbent bed as the water passes through the bed;

(iii) Recycling the initial portion of the effluent which issues just after the water and sucrose solute begin to show in the effluent, in order to extract the impurities which in that portion are higher proportionately than in the succeeding portion;

55 (iv) Fractionating the effluent to collect the high-purity portion thereof separately from the mineral salt solute and non-sugar containing liquor, so that the high-purity portion can subsequently be separately boiled and crystallized.

60 Although the procedure in different sugar factories differs in a number of respects, it will be helpful to describe a general process or procedure in a raw cane sugar factory in order that the applicability of the present process to sugar manufacturing may be fully understood.

As illustrated in Fig. 1, juice of relatively high acidity 65 extracted by the mill is weighed on scales 10 and then limed in tanks 12 to approximately 7.4 pH and heated to 214-220° F. in heaters 14. It is flashed and delivered

to continuous clarifiers 16 from which the clarified juice is drawn off. The sludge is delivered to a vacuum filter 18 in which the remaining juice is mostly drawn off and the mud cake "sweetened off" by application of a spray of water which lowers the sucrose content.

The clarified juice is generally of 14-15 Brix. It is delivered to a supply tank 20 (with the sweetened water from the vacuum filter, if desired) and then to a multiple effect evaporator 22 in which it is subjected to a series of stages of boiling, each being at an increasing stage of vacuum. The finally concentrated liquor (termed syrup) at about 60 to 70 Brix is held in supply tank 23. Subsequent concentration of this syrup involves the development of crystals in "single effect" cells 24 (vacuum pans) in which exact control can be maintained under vacuum of 26.5 to 27.5 inches of mercury.

The mixture of crystals and mother liquor from the vacuum pan 24 is optionally delivered to crystallizers 26 for further crystallization. In centrifugals 28 the crystals are separated from the mother liquor of the resulting massecuite. The expelled liquid or "A" molasses is then delivered to the "B" vacuum pan 30 for further concentration, alone or with syrup from the supply tanks 23. The resulting mixture is treated in the crystallizers 26; and the sugar crystals are separated from the "B" molasses in the centrifugal 28.

Clarification of the juice—after heating and liming—is not, as a rule, highly efficient in the removal of insoluble material. Certain impurities that are insoluble at this stage, including colloids and other substances of specific gravity closely approximating that of the surrounding liquid, pass through into the clarified liquid. As the juice becomes concentrated in its boiling in the evaporator into syrup, the unremoved insoluble impurities become more concentrated and they exert an effect adverse to crystal development and curing of the sugars. This adds especially to the difficulty of final-stage crystallization and limits the practical end point of sugar recovery.

Moreover, during the process of concentration by boiling in both the evaporator and in the vacuum pans (the latter reducing the water content of the massecuite to approximately five percent) there is usually a considerable additional precipitation of non-sugars and various forms of impurities.

As a result of these two sorts of impurities (precipitates and insolubles) in the latter stage liquors, i. e., in the "A" and "B" molasses (and because of the concentration of these impurities, especially in the "B" molasses) the usual procedure of boiling the "B" molasses in the vacuum pan involves excessive contamination and a relatively high degree of viscosity. Such contamination and viscosity retards the boiling process and it also actually terminates crystal formation in the pan sooner than that which would be attainable in the absence of these impurities.

The steps preceding boiling the molasses in both the "A" and "B" stages are not so seriously affected by the insoluble and precipitated impurities because, first, they are not in such concentrated form and, second, the purities of the liquors and massecuites are much higher at this stage and can be handled and adequately cured in the centrifugal without trouble. Therefore, there is no special benefit, in the production of raw sugar, in removing either the insoluble impurities or the soluble mineral salts prior to the "B" molasses.

Besides the insoluble and precipitated impurities above referred to, a third kind of impurity, namely, mineral salts which are still in solution, exert a particularly serious retardment on the final stage of crystallization.

For the purpose of removing the soluble mineral salts and certain other non-sugars, I employ an ion exclusion process after having clarified the molasses, as will now be described.

Referring to Fig. 2, the molasses is introduced into a mixing tank 40 through pipe line 41 by operating valve 42. In this tank, the molasses is diluted to approximate-

ly 40-50 Brix. Either milk of lime (CaO) or suitably fired magnesium oxide (MgO) is introduced through pipe line 43 by operating valve 44 so as to raise the pH to between 8.5-9.5 approximately. The most advantageous amount of alkalinity varies with the quality and characteristics of the liquor and the impurities to be dealt with. Phosphoric acid is then added through pipe 45 by operating valve 46 to the extent of establishing a pH of 6.7-6.9. The temperature is raised by heating with steam coils 47 while the material is vigorously stirred by stirrers 48. The prepared liquor is dropped into receiving tank where it is further stirred and where a flocculating aid is added, such as an organic polyelectrolyte, for example, having the characteristics of adding to precipitated flocs and entraining the more finely suspended materials such as colloids. The temperature is maintained or adjusted to 180° F. in the tank which serves as supply tank for the clarifier or, in the embodiment illustrated, centrifugal separators.

In clarifying molasses solutions, excellent results are obtained by the use of a solid bowl centrifugal separator 50 having a cylindrical bowl with an imperforate side wall 51 and annular inturned flanges 52, 53 at its top and bottom edges. At the bottom of the bowl there is an annular hood 54 having its outer edge inclined downwardly and close to the inner wall of the bowl. This hood is secured to the base of the bowl by a perforated annular plate 55. The hood and perforated plate serve to uniformly distribute the incoming liquor and accelerate it to the approximate peripheral speed directly adjacent to the inner surface of the bowl. In order to insure maintaining of high centrifugal force throughout the flow, an annular baffle plate 56 is secured close to the upper head. This plate 56 extends so that its outer edge is located at approximately half of the depth of the material under treatment while the inner edge extends an inch nearer the axis than the surface of the liquor under treatment. The bowl, hood 54, plate 55 and baffle 56 are all rigidly affixed to an axle or drive shaft 57 and are balanced to rotate without vibration.

The solid separator bowl is rotated to produce a force about 2,000 times gravity or more and is preferably driven by an electric motor 58 through a fluid coupling 58c; but other driving means may be employed and other methods of clutching or coupling may be used.

The solid separator bowl is operated at full speed and flow rate until the liquor outflow shows evidence of carry-over of insoluble material. At that time inflow of liquor is shut off and water is introduced to remove the remaining liquor. As the machine is stopped the sludge is removed, preferably by a discharge plow similar to those used on sugar curing centrifugals. The clarified liquor discharges over the top flange 52 and passes down into the gutter 50g from whence it flows into a receiving tank (not shown) while the sludge is dropped into a conveyor 59.

Since the sludges delivered into the scroll conveyor 59 contain a considerable amount of sucrose, they are delivered to the vacuum filter 18 (Fig. 1) where, in carrying over the surface of the drum the sludge is sweetened off through the application of a spray, or several sprays, which wash out the sucrose bearing liquor.

The clarified molasses is delivered to a supply tank 60 wherein its temperature is adjusted to about 180° F. by a thermostat 62 controlling the flow of steam in a line 64 connected with the tank.

The clarified molasses from the supply tank 60 of approximately 40 Brix and at a temperature of approximately 180° F. or higher is delivered through a pipe 66, upon opening a control valve 68 therein, to a column 70 containing a resin bed 72.

During passage of the molasses through the resin bed, the low polar sucrose solute is adsorbed and/or retained by the resin while the more highly ionized

solutes, i. e., of the relatively high polar position, such as mineral salts and certain non-sugars are excluded by the resins and pass on with the effluent through the pipe 74 upon opening of valve 76 therein.

When it appears that the adsorbing capacity of the resin bed has been reached or is closely approached, the flow of molasses through the resin bed is stopped by closing valves 68 and 76, and is followed by a water rinse introduced from a hot water supply tank 80 through a pipe 78 upon opening a valve 79 therein. During this rinse, the sucrose solute which has been adsorbed by the resin is replaced by water and follows the excluded run-off, but is collected as a separate fractional effluent.

Some degree of overlapping occurs between the fraction of excluded initial effluent and the final fraction bearing the low ion sucrose liquor. This relatively nominal amount of intermediate mixed fractions is recycled so as to avoid sucrose loss, by opening valve 82 in pipe line 84 returning to tank 60. When the effluent appears clear enough the recycling valve 82 is closed and the valve 86 in pipe 88 is opened to separately collect the demineralized liquor.

While several types of resin can be employed, satisfactory results have been obtained in the use of a high porosity, sulfonated polystyrene resin, cross-linked at about 4, and of 50-100 mesh. The low cross-linkage (indicating high porosity and adsorbing capacity of resin matrix) is structurally selective by control of the amount of divinylbenzene added prior to sulfonation.

One example of a resin that has been found suitable, but without limitation of the invention thereto, is sulfonated styrene divinylbenzene copolymerize, which has 1.8 sulfonic groups per benzene ring. The equivalent weight in solution is 2.2 equivalents per liter. In conformity with the requirements of this invention and the adsorption of low polar sucrose solute, it is essential that resin porosity is provided adequate to accommodate the molecular structure of sucrose. Other resins having said properties may be used.

The amount of molasses treated in each cycle is gauged according to the adsorbing capacity of the resin bed. With constant flow rate and predetermined amount of water rinse for removal of the sucrose solute from the resin bed, the cycles are accurately timed and are automatically controlled. Retaining resin stability and functional effectiveness is accomplished by periodic rinse of the resin with a salt (NaCl) solution from a supply tank 90 through pipe line 92 opening a valve 94 therein, while valves 68 and 79 are closed. The salt rinse is run-off through a separate outlet pipe 96. Since no ion exchange takes place in the sense that applies to ion exchange processes, no regenerants are required.

Upon completion of the demineralization treatment, the density of the finally treated liquor is somewhat low for direct introduction into a vacuum pan for the final boiling and development of crystals. Therefore, a small multiple effect evaporator 97 is provided into which the clarified and demineralized liquor is delivered from the exclusion unit. This concentrates the liquor to a suitable density of about 80 Brix.

The clarified, demineralized, reconcentrated liquor is delivered to the vacuum pan supply tanks 98 which supply the "C" vacuum pan 99. Development of the crystals proceeds under these conditions rapidly and to a greater extent than is possible when the insoluble impurities and mineral salts are present as in usual practice.

Among the principal advantages of the ion exclusion method of removing mineral salts and certain other non-sugars, from sugar solutions, as compared to ion exchange are:

(a) More rapid, and greater frequency of, cycles and, therefore, less equipment and lower cost.

(b) Simpler and easier control.

(c) Elimination of backwash prior to regeneration, as required for ion exchange.

(d) Greatly reduced dilution and, therefore, less evaporation required.

(e) Avoidance of low pH phases of cycles and associated susceptibility to sucrose inversion.

(f) Elimination of requirement for cooling. Preferred temperature during the ion exclusion cycle is at least 180-185° F.

(g) No regenerants required.

From the foregoing it will be understood that because the sucrose solute is adsorbed while the impurities are excluded by the resin in the demineralization stage, I have found it most practical and advantageous to apply the demineralization stage at that place or to those liquids in the manufacture of sugar where the percentage of impurities per unit of volume is relatively high and the percentage of sugar content is relatively low. In cane sugar practice that point is reached with the "B" molasses.

Similarly, affination liquors contain a relatively high percentage of impurities but have higher sugar content than "B" molasses. An equivalent point is reached in the final molasses in beet sugar practice, despite the fact that final molasses from beets commonly has higher purity, i. e., contains more sugar than cane "B" molasses. The greater sugar content in final molasses from beets is due largely to the difficulty in handling impurities from beets which are different in nature from cane impurities.

To all of these, and in fact to any material, solution or liquor where substantially equivalent limits and conditions of purity and impurities exist, my invention is applicable to great advantage.

To further indicate the value and importance of treating "B" molasses and the like, a contrast with known ion-exchange processes may be drawn. In ion exchangers, the impurities are broken down and drawn into the type of resin there employed. The sugar remains and passes on. Hence, a liquor containing a low percentage of impurities can more readily be treated, although other difficulties may arise due to the much larger volume which must be handled and less favorable temperature conditions and pH values, especially in treating juices.

Although my process is especially aimed to increase the yield of raw sugar from cane because that is the basis for more profitable operations by reduction of unit cost, other important results flow from the invention. The resulting molasses is purer and can be used in the food industry where molasses heretofore has not been satisfactory because of the still-retained impurities. Also, certain bacterial impurities are no longer present, providing a more sterile molasses and enabling the molasses to be stored longer without spoiling. Further reduction in bacterial impurities can be accomplished by treating the clarified and demineralized molasses with ultra-violet light and using sterile water.

In addition, the impurities separated out in the excluded liquor are useful with food for cattle and poultry where heretofore the whole molasses at higher cost had to be used or further costly processing was necessary to extract the desired substances, vitamins and minerals.

Other indirect benefits of this process are evidenced by the completely clean final crystallizer sugars, sometimes designated "C" or "D" sugars. Ordinarily these sugars are highly contaminated and are far too low in grade and purity to be sold directly commercially. The usual practice is to return the low grade (crystallizer) sugars as seed footings for the "A" and "B" vacuum pan boilings. However, this means in ordinary practice and under average conditions that most of the tenacious refractory impurities are recycled. To a considerable extent they lower the refining qualities of the commercial raw sugars. The clarification and demineralization process of this invention eliminates this recycling of impurities.

Another result is that crystallization, especially in the final stage, proceeds much more rapidly and further than is otherwise the case.

Again the final molasses instead of being the usual highly contaminated blackstrap is, on the contrary, a clean food-grade product, high in vitamins and suitable as a food component.

Many modifications within the scope of the invention will occur to those skilled in the art. Therefore, the invention is not limited to the precise form of the embodiment disclosed.

What is claimed is:

1. The process of clarifying and demineralizing "B" molasses, affination liquors and like sugar bearing solutions which contain a similarly comparatively high percentage of impurities from previous crystallization, comprising removing precipitated and insoluble impurities to clarify the solution, subsequently passing the clarified solution through a bed of low cross-linked high porosity highly ionized resin having the property of adsorbing sugar and by ion-exclusion excluding impurities, collecting the excluded-impurity-containing effluent, rinsing out the sugar by passing water through said resin bed, and collecting the sugar-bearing rinse separately for subsequent extraction of sugar, and maintaining the temperature during the ion-exclusion stage and rising up to at least 180° F.

2. The process as claimed in claim 1 in which the solution is diluted to about 40 to 50 Brix approximately, prior to clarification.

3. The process as claimed in claim 2 in which the clarification comprises adding basic and acidic reagents giving a resultant clarified solution having a pH of about 6.7-6.9 approximately, adding a flocculating medium and removing the precipitated and insoluble materials.

4. The process as claimed in claim 3 in which the bed comprises a high porosity, highly ionized, sulfonated styrene divinylbenzene copolymerize resin.

5. The process as claimed in claim 1 in which the clarification comprises adding basic and acidic reagents giving a resultant clarified solution having a pH of about 6.7-6.9 approximately, adding a flocculating medium and removing the precipitated and insoluble materials.

6. The process as claimed in claim 5 including collecting an initial small fraction of the sugar-bearing rinse, and recycling said small fraction through said resin bed, and collecting the remainder of the sugar-bearing rinse separately for subsequent extraction of sugar.

7. The process as claimed in claim 6 in which the bed comprises a high porosity, highly ionized, sulfonated styrene divinylbenzene copolymerize resin.

8. The process as claimed in claim 1 in which the clarification comprises adding basic and acidic reagents giving a resultant clarified solution having a pH of about 6.7-6.9 approximately, adding a flocculating medium and removing the precipitated and insoluble materials, sulfonated styrene divinylbenzene copolymerize resin.

9. The process of producing purified molasses from impure materials such as "B" molasses, affination liquors and like sugar bearing solutions which contain a similarly comparatively high percentage of impurities from previous crystallization, comprising removing precipitated and insoluble impurities to clarify said impure material, passing the said clarified impure material through a bed of low cross-linked, high porosity, highly ionized resin having the property of adsorbing sugar and by ion-exclusion excluding impurities, collecting the excluded-impurity-containing effluent, rinsing out the sugar from the resin by passing water through said resin bed and collecting the sugar bearing rinse separately, and maintaining the temperature during the ion exclusion stage and rinsing up to at least 180° F.

10. The process as claimed in claim 9 in which the bed comprises a high porosity, highly ionized, sulfonated styrene divinylbenzene copolymerize resin.

11. The process as claimed in claim 9 including subjecting the purified molasses to ultra-violet light to sterilize said purified molasses.
